(57) **CLAIM**

The ornamental design for an enclosure for electronic device,
as shown and described.

DESCRIPTION

FIG. 1 is a perspective view of an enclosure for electronic device depicting a first embodiment of a new design;

FIG. 2 is a top plan view thereof;

FIG. 3 is a bottom plan view thereof;

FIG. 4 is a front elevational view thereof;

FIG. 5 is a rear side elevational view thereof;

FIG. 6 is a left side elevational view thereof; and,

FIG. 7 is a right side elevational view thereof.

The broken line portion of the drawings is included to show
unclaimed portions of the enclosure for electronic device
which form no part of the claimed design.
